UNITED STATES PATENT OFFICE.

JOHN P. BUTCHER, OF CANTON, OHIO.

COLLAPSIBLE CRATE.

Application filed August 9, 1923. Serial No. 656,598.

This invention relates to shipping crates and more particularly to a collapsible crate especially designed for shipping parcel post packages and the like, and has for its objects

5 to provide a crate of this character comprising a folding frame preferably formed of twisted wire, and provided with a covering of canvas or the like connected thereto and arranged to fold with the frame.

10 The above and other objects are attained by providing a frame having two rigid sides and two hinged folding sides with means for holding the same in extended position and by providing a bottom formed of two

15 members hingedly connected together and to the lower edges of the rigid sides, a top being provided formed of two similar members arranged to be hingedly connected to the rigid sides of the frame at different 20 points, a canvas cover being connected to the frame and arranged to be folded therewith.

An embodiment of the invention is illustrated in the accompanying drawing, in 25 which—

Figure 1 is a perspective view of the frame of the crate in the opened or extended position;

Fig. 2, a perspective view of the complete 30 crate in the open position;

Fig. 3, a side elevation of the frame of the crate in the folded position;

Fig. 4, a top view of the crate in folded 35 position;

Fig. 5, a detail perspective view of one of the hinged joints;

Fig. 6, a detail sectional view showing the connection of the canvas 26 to the side frame 1.

40 Similar numerals refer to similar parts throughout the drawing.

The frame of the crate is preferably formed of twisted wire to give the same combined strength and lightness of weight 45 and includes two rigid side portions each comprising a rectangular frame 1, preferably braced by the cross rods 2 which connect opposite corners thereof.

The rigid frames 1 are connected together 50 by the upper, lower and intermediate pairs of hinged rods 3, each of which is hingedly connected at its outer end to one of the side frames as at 4, each pair of rods being hingedly connected together as at 5.

55 The intermediate rods 3 are connected to the frame members 1 at points above the

centers of said frames, in order to permit the bottom to fold inwardly beneath said rods, as will be later described.

A latch 6 is provided at each hinged joint 60 5 of the upper rods 3 for the purpose of rigidly holding these rods in extended position. Each of these latches is provided with a pair of spaced ears 7 at one end which are pivotally connected to one of the rods 65 3 adjacent to the hinged joint 5 thereof as at 8, a similar pair of ears 9 being provided upon the other end of the latch for engagement with the other rod 3 upon the opposite side of the hinged joint 5 when the crate 70 is in the open position.

The bottom of the frame comprises a pair 75 of similar U-shaped rods 10 hingedly connected to the lower corners of the rigid frames 1, at their ends, as shown at 11, and hingedly connected together at their central portions, as shown at 12.

The top or lid of the crate comprises a pair of substantially U-shaped rods 13 and 14, each of which is provided at its ends 80 with the eyes 15 arranged to be engaged in the hooks 16, 17 or 18 which are formed at spaced intervals from the top of the rigid frames 1 to a point near the hinged connections of the intermediate hinged rods 3. 85

The rod 13 is provided with a loop 19 arranged to receive the eye 20 upon the rod 14 when the crate is in the closed position, a padlock 21 or the like being connected 90 to the eye 20 to hold the lid in this position and prevent access to the interior of the crate.

The canvas covering indicated at 21^a is 95 connected to the four sides of each rigid frame 1, as shown at 22, and is also preferably connected to the cross bars 2 thereof as shown at 23. This canvas cover is also connected to each of the hinged rods 3 near the outer ends thereof, as shown at 24. The bottom frames 10 are also covered with canvas as shown at 25, this canvas covering being arranged to fold inward as the crate is collapsed.

A canvas covering 26 is connected to the 100 edges of each lid portion of the frame and the free end thereof is connected to the inside of the adjacent rigid frame 1, as shown by the dotted line at 27 in Fig. 2. This permits the attachment of the hinged lids to any of the hooks 16, 17 or 18 as may be 105 desired, according to the height of the contents of the crate. 110

In collapsing the crate, the lid members 13 and 14 are dropped downward inside of the crate and the bottom members 10 are folded upward inside of the crate, while the hinged rods 3 are folded inward, collapsing the crate as shown in Figs. 3 and 4.

As best shown in Fig. 3, it will be seen that the intermediate hinged rods 3 are located above the center, in order to permit the hinged bottom members 10 to fold upward beneath the same.

When the crate is in the opened or distended position and the latches 6 are moved into operative position, the canvas covering 15 will be stretched taut and the frame held in opened position, permitting the crate to be filled, after which the cover sections 13 and 14 are attached in the hooks 16, 17 or 18, depending upon the height of the contents 20 of the crate and the covers are closed and attached together as by the lock 21.

I claim:—

1. A collapsible crate including two rigid side frame members, rods hingedly connected together and to the side frame members, two bottom members hingedly connected together and to the lower edges of the side frame members, two cover members arranged to be hingedly connected to the

side frame members at different heights, 30 means for connecting the free edges of the cover members together and a flexible covering upon the frame arranged to be stretched when the frame is opened.

2. A collapsible crate including two rigid 55 rectangular side frames, rods hingedly connected together and to the side frames, two bottom members hingedly connected together and to the lower edges of the side frame members, hooks formed at intervals 40 upon the side frames, two cover members provided with eyes for selective engagement with said hooks and a flexible covering upon the frame arranged to be stretched when the frame is opened. 45

3. A collapsible crate including two rigid rectangular side frames, rods hingedly connected together and to the side frames, two bottom members hingedly connected together and to the lower edges of the side 50 frames, hooks formed upon the side frames, two cover members provided with eyes for engagement with said hooks and a flexible cover upon the frame arranged to be stretched when the frame is opened. 55

In testimony that I claim the above, I have hereunto subscribed my name.

JOHN P. BUTCHER.
